COMBINED RAZOR BLADE DISPENSER AND DATE INDICATOR

Gordon R. Muncy, 5061 Scott Circle,
La Palma, Calif. 90620

Filed Feb. 22, 1972, Ser. No. 228,478

Term of patent 14 years

Int. Cl. D9—03

U.S. Cl. D9—224

FIG. 1 is a perspective view of a combined razor blade dispenser and date indicator showing my new design looking in the direction of the top, front, and right side thereof;

FIG. 2 is a perspective view thereof looking in the direction of the bottom, rear, and right side thereof;

FIG. 3 is a top plan view thereof; and

FIG. 4 is a left side elevation view thereof.

I claim:

The ornamental design for a combined razor blade dispenser and date indicator, as shown and described.
